A. E. L. SCANES,
STEAM CONDENSER APPARATUS,
APPLICATION FILED NOV. 1, 1915.

1,353,855.

Patented Sept. 28, 1920.

UNITED STATES PATENT OFFICE.

ARTHUR EDWIN LEIGH SCANES, OF ASHTON-ON-MERSEY, ENGLAND, ASSIGNOR TO THE BRITISH WESTINGHOUSE ELECTRIC & MANUFACTURING COMPANY, LIMITED, OF LONDON, ENGLAND.

STEAM-CONDENSER APPARATUS.

1,353,855.

Specification of Letters Patent. Patented Sept. 28, 1920.

Application filed November 1, 1915. Serial No. 59,015.

To all whom it may concern:

Be it known that I, ARTHUR EDWIN LEIGH SCANES, a subject of the King of Great Britain, residing at Ashton-on-Mersey, England, 5 have made a new and useful Invention in Steam-Condenser Apparatus, of which the following is a specification.

This invention relates to steam condensers of either the surface or jet type.

10 To operate a steam condenser at a high vacuum it is necessary to employ some form of air extractor which may be either of the reciprocating or rotary type or be a steam or water ejector, or any combination of 15 these.

For certain types of air extracting apparatus (such for example as those utilizing a water jet on which the vapor condenses and is lost, or those using steam jets or 20 piston pumps in which case vapor lowers their capacity), it is advantageous to reduce to a minimum the amount of vapor contained in the air leaving the condenser. Various means have been suggested for accomplishing this such as a series of baffle plates in the 25 steam space of the condenser, the object being to cause the air and incondensable gases and vapor to pass over a cooling surface of the lowest possible temperature. Weirs 30 have also been placed in the bottom of surface condensers with the object of cooling the condensate which is afterward used in the air extractor, thus reducing the vapor tension and steam content of the mixture to 35 be removed. In all these arrangements ample passages have been left to avoid impeding the flow of the gases and consequent loss of vacuum between the condenser steam inlet and the air outlet. With all these 40 arrangements, however, it is always possible to entrain a large amount of uncondensed steam with the air removed, and also if the vacuum in the air pump is a high one, there is a risk of re-evaporation of the condensate 45 in the condenser. Moreover, the majority of these arrangements have the disadvantage of cooling the condensate unduly with consequent loss of thermal efficiency in the feed water to the boilers.

50 The object of the present invention is to overcome these disadvantages and to increase the weight of air removed by the air extracting apparatus while maintaining a high hotwell temperature without re-evaporation.

According to this invention a cooling chamber is provided located either within or external to the main steam condensing space of the condenser through which chamber in the case of a surface condenser a portion of the cooling tubes, or in the case of a jet condenser a portion of the injection water passes. The said chamber communicates through a restricted opening with the steam space of the condenser at the point 60 at which it is required to remove the air and incondensable gases. This restricted opening is conveniently formed as a converging nozzle and its object is to produce a pressure drop of an approximately constant amount between the steam space of the condenser and the interior of the cooling chamber. At another suitable place in the cooling chamber a connection of ample proportions is made to a suitable air extracting 65 device. As it will be known in any given case what amount of air may be normally expected in the condenser, and as it will be also known approximately what the vacuum will be in the condenser it will be possible 70 to calculate approximately the area of the restricted opening which will pass the volume of saturated air thus arrived at with a predetermined drop of pressure. Should now the vacuum in the air extractor be higher 75 than the theoretical vacuum corresponding to the condensate in the condenser, any tendency to re-evaporation of the latter will be very largely prevented owing to the limitation of the quantity of mixture which can 80 pass through the restricted opening within the limits of pressure difference allowed under working conditions, and further, any vapor which does pass this opening will be 85 re-condensed inside the cooling chamber before it can pass to the air extractor, and will be returned from the said chamber to the condenser through a suitable water sealed 90 pipe or passage.

Various ways in which the invention may 100 be carried into effect are shown diagrammatically in the several figures of the accompanying drawing in which like reference letters indicate similar parts.

Figure 1 shows one form of the invention 105 used in connection with a surface condenser of a well known type, the steam inlet of which is shown at G, the nest of tubes at H, and the condensate discharge at J.

"A" in Fig. 1 shows a common type of 110

baffle plate made of some suitable material such as galvanized steel plating which may extend throughout the length of the condenser and forms with the condenser shell 5 an additional or interior cooling chamber C. In this baffle is introduced the restricting nozzle "B" through which the non-condensable gases pass into the cooling chamber "C" wherein the vapor content of the gases 10 is reduced to the saturation point approximately corresponding to the cooling water temperature passing through the tubes "C." Such vapor when condensed is returned through a well-known form of seal "D" to 15 the main condensate discharge "J" of the condenser. The non-condensable gases are withdrawn by the unrestricted passage "E" by any suitable form of air pump or air extractor.

20 Fig. 2 shows a structural modification of Fig. 1 in which the galvanized steel plate "A" is replaced by a flanged pipe "F," the other details remaining the same. This construction has certain advantages over the 25 construction shown in Fig. 1, as in the latter it is obviously necessary to make a good joint both with the shell of the condenser at two places and with the tube plates, whereas in the construction shown in Fig. 2 although 30 it is still necessary to make good joints, these joints can be more easily machined and fitted. It is preferable that the cooling chamber should run the full length of the condenser, but this is not necessary.

35 In Fig. 3 the cooling chamber is shown external to the condenser.

Fig. 4 shows a cooling chamber in conjunction with a jet condenser the operation being substantially the same as in the previous figures, with the exception that the 40 cooling chamber is cooled by a water jet K in a similar manner as the main condenser.

From the foregoing it will be readily understood that this invention consists in the provision of a cooling chamber either internal or external to the condenser communicating with the steam space of the condenser through a restricted opening of a predetermined area, so as to cause an appreciable 45 difference between the pressure in the condenser and that in the cooling chamber and having an air outlet of ample proportions

between the cooling chamber and the air extracting device.

Several arrangements, such for instance 55 as those hereinbefore mentioned, have been proposed for cooling the air and water in a condensing apparatus, but in all of these the object has been to cool the condensate and to avoid as far as possible a drop in pressure, 60 whereas the object of this invention is to maintain the condensate as hot as possible and to create a drop in pressure by means of a restricted opening as hereinabove described.

Having now particularly described and ascertained the nature of my said invention and in what manner the same is to be performed, I declare that what I claim is:

1. In combination with the main cooling chamber of a condenser having a steam inlet and condensate outlet, an additional cooling chamber in restricted communication with the main chamber and having a relatively unrestricted outlet for connection with an 70 air extracting device whereby during the operation of said air extracting device a less pressure will be maintained in the additional than in the main chamber, cooling means in said additional chamber and sealed means for delivering condensate from the additional chamber to the condensate outlet 75 of the main chamber.

2. In combination with the main cooling chamber of a surface condenser having a 80 steam inlet and a condensate outlet, a relatively small cooling chamber of the surface type, additional to the main chamber, in restricted communication therewith and having a relatively unrestricted outlet for connection 85 with an air extracting device whereby a less pressure may be maintained in the additional than in the main chamber and sealed means for delivering condensate from the additional chamber to the condensate outlet 90 of the main chamber.

In testimony whereof I have hereunto subscribed my name this eighteenth day of October, A. D., 1915.

AUTHUR EDWIN LEIGH SCANES.
